UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

FILLING-FORK GRID FOR LOOMS.

Application filed March 15, 1926. Serial No. 94,922.

This invention relates to looms and more particularly to the mounting of the filling fork grid on the lay. It is now the common practice to provide looms with a filling fork which cooperates with a filling fork grid 5 mounted on the lay to determine whether or not filling has been laid in the shed, and on its absence to effect a change in loom operation.

10 In general practice the filling fork grid has been ordinarily mounted on the back plate of the shuttle box and in some instances it has been mounted directly on the lay. Inasmuch as the tines of the filling fork must 15 cooperate with the spaces between the grid bars, it has been suggested heretofore to provide means for adjusting the filling fork grid laterally, that is, in a direction transversely of the loom.

20 When the shuttle is picked during the weaving operation, the back of the shuttle usually rests upon the front face of the reed, and at the end of the reed the filling fork grid is usually located. Should the 25 filling fork grid have the front faces of its bars projected beyond the plane of the front face of the reed, serious injury to the shuttle is liable to result. On the other hand, should the front face of the grid be too far back of 30 the plane of the reed, the filling may not be positioned to effect a sufficient tilting movement of the filling fork as the lay moves frontwardly. Since the function of the filling fork grid is to hold the filling in position 35 to tilt the filling fork on beat-up, the plane of the front face of the grid should be substantially in the plane of the front face of the reed, so that on the beat-up, the parts will perform their proper functions. The 40 reed, however, is mounted between the lay and the top bar thereof, and owing to the constant recurring beat-up movement exerted on the filling thread, it is liable to become worn or displaced from its original 45 position, with the result that the front face of the grid may project frontwardly or beyond the plane of the front face of the reed and cause injury to the shuttle during its picking movements.

50 It is also desirable that the filling fork grid be not only mounted for position relative to the front face of the reed to overcome the above objections but that it shall be laterally movable, that is, transversely of the loom, to bring the spaces between the

grid bars into cooperating relation with the tines of the filling fork.

One of the objects of the present invention is to provide a grid mounted on the lay which will enable the grid to be properly positioned relative to the front face or plane of the reed and also relative to the tines of the filling fork. In accordance with the preferred form of the invention, the filling fork grid is provided with a base portion which is secured to the lay to permit movement of the grid bodily towards and from the front of the lay into the plane of the reed, and a further feature of the invention consists in securing the filling fork 60 grid to the lay with the above characteristic capacity for movement into the plane of the reed, and also in a lateral direction, that is, 65 transversely of the loom.

The invention and novel features thereof 70 will best be made clear from the following description and the accompanying drawings of one good form of the filling fork grid mounting.

In the drawings:

Fig. 1 is a perspective view of sufficient 75 portions of a loom to show the present invention associated therewith;

Fig. 2 is a sectional plan view through the 80 reed and grid, showing the front face of the grid and the front face of the reed in their desired coinciding planes; and

Fig. 3 is a detail view looking from the 85 rear of the lay and showing the grid mounting.

The filling fork is usually employed to either stop the loom on failure of filling or effect replenishment but since such mechanism forms no part of the present invention which more directly relates to the grid 90 mounting, such features are not herein shown.

The lay swords 1, only one of which is shown, have secured thereto the usual lay 2, which is provided with shuttle boxes 3. The 100 race 4 on which the shuttle rests as it is picked, is provided with the usual groove to receive the lower edge portion of the reed 7, while the upper edge portion of the reed is retained in a groove in the top rail 105 5, but since such features are well-known and the details thereof form no part of the present invention, no further description of these matters appears necessary. The top or hand rail 5 is secured to the upwardly 110

extending arm 6, as usual, and the lay is given its usual beat-up movements through a pitman or arm 8 which may be actuated from the crank shaft.

5 Mounted at the front of the loom is the usual filling fork slide 9 on which is pivotally mounted the filling fork 10, the tines 11 of which extend downwardly for cooperating relation with the grid during beat-up movement of the lay.

10 The grid 12 may be of any usual character but is herein shown with the grid bars 13 spaced apart and extending from the upper and lower portions of the grid 15 to receive the tines of the filling fork should filling not be laid in the shed, and yet present the filling to the filling fork to tilt it should filling be laid in the shed. The filling fork grid 12 is provided with a supporting base 14 which as shown may extend rearwardly of the lay, and is provided with a slot 19 which extends frontwardly and rearwardly relative to the lay.

15 In accordance with one feature of the present invention, the filling fork grid is to be supported from the lay for movement frontwardly and rearwardly relative to the plane of the front face of the reed, and as one good form of means to this end 20 the present invention provides a bracket 16 having a supporting head portion 15 on which rests the supporting base 14 of the grid, and in order that the grid may be guided in its movement towards and from 25 the plane of the reed, guiding means are provided between the head 15 and the base of the grid. In the present instance, such guiding means is secured by providing the supporting head 15 with the side flanges 30 35 40 45 50 55 60

17, between which the base 14 of the grid may be moved frontwardly or rearwardly and finally secured in its desired position with the front face of the grid in the plane of the front face of the reed, by means of a securing bolt 18 which passes through the elongated slot 19 formed in the base of the grid and into the head 15 of the bracket. The bolt 18 may be of usual construction and have a nut 20 by which the base of the grid and the head of the bracket may be clamped in fixed position.

55 From the construction described it will be apparent that should the reed become worn by its recurring contacts with the shuttle, or should the reed mountings wear, the filling fork grid may be readily moved to bring its front face into alignment with the plane of the front face of the reed by manipulation of the securing bolt, and thereupon the parts may be secured in fixed relation.

60 It frequently happens that the tines of the filling fork and the spaces between the bars of the filling fork grid may not be properly related, owing to the wear of the parts connected to the lay. Indeed it sometimes

happens that the lay itself may deviate from its original course to and from the front of the loom and be laterally displaced somewhat, and to meet this condition the present invention provides means for adjusting the 70 bracket on which the filling fork grid is mounted.

In the present instance of the invention, the bracket 16 extends downwardly and laterally from the supporting head 15 and is 75 provided with slots 22 substantially at right angles to the direction of the slot 19 in the base of the filling fork grid, the construction being such that should the tines of the filling fork and the spaces in the filling 80 fork grid not properly register on a beat-up movement of the lay, the bracket 16 may be readily moved in a lateral direction or transversely of the loom to rectify the 85 alignment, and should the wear of the parts necessitate rearrangement of the filling fork grid relative to the bracket, in a frontward or rearward direction, to bring the front face of the filling fork grid into the plane 90 of the front face of the reed, manipulation of the bolt 18 readily effects this result.

95 From the construction described as one good practical form of the present invention, it will be apparent that the filling fork grid may be readily moved in a direction towards and from the front of the lay to bring the front face of the filling fork grid into the plane of the front face of the reed, and is readily moved in a lateral direction or transversely of the loom to rectify the alignment 100 of the openings of the grid with the tines of the filling fork, and after such rectification the parts may be secured rigidly in their new positions.

105 What is claimed is:

1. In a loom, the combination of the lay having a reed, a filling fork grid, and means for securing the grid to the lay in different positions, comprising a bracket having a grid supporting head, devices for securing the bracket in different positions transversely of the loom, a supporting base upon the grid constructed to fit the supporting head for movement towards and from the plane of the reed, and means for securing the base to the bracket head in different positions relative to the plane of the reed.

110 2. In a loom, the combination of the lay having a reed, a filling fork grid having a supporting base, a bracket adapted to be secured to the lay in different positions transversely of the loom and having a head, cooperating means between the head and base of the grid for guiding the latter in its movement towards and from the front of the loom, and means for clamping the base of the grid to the head of the bracket in different positions relative to the plane of the reed.

115 3. In a loom, the combination of the lay,

a filling fork grid having a supporting base, a grid supporting bracket secured to the lay and having a head to receive the supporting base of the grid and permit movement of the grid towards and from the front of the lay, and means for clamping the grid supporting base to the bracket head in different positions relative to the front of the lay.

4. In a loom, the combination of the lay having a reed secured thereto, a filling fork grid, and devices for securing the grid to the lay in different fixed positions relative

to the reed, one towards and from the adjacent edge of the reed and the other towards and from the front surface plane of the reed that the grid may be properly positioned for the filling fork and the front surface plane of the grid may be positioned into the plane of the front surface of the reed to compensate for wear of the reed.

In testimony whereof, I have signed my name to this specification.

HARRY A. DAVIS.
